UNITED STATES PATENT OFFICE

115,879

DESIGN FOR A WASHING MACHINE

Michael Phillip Gaultier, St. Paul, and Merrill
Laffayette Alexander, Minneapolis, Minn.

Application May 11, 1939, Serial No. 84,924

Term of patent 14 years

To all whom it may concern:

Be it known that we, Michael Phillip Gaultier and Merrill Laffayette Alexander, citizens of the United States, residing at St. Paul, in the county of Ramsey, State of Minnesota, and Minneapolis, in the county of Hennepin, State of Minnesota, respectively, have invented a new, original, and ornamental Design for Washing Machines, of which the following is a specification, reference being had to the accompanying drawing, forming part thereof.

Fig. 1 is a perspective view, Fig. 2 is a front elevational view, and Fig. 3 is an end elevational view of a washing machine, showing our new design. The dotted lines illustrate plungers. The dominant features of our design, however, reside in the portions shown in full lines.

We claim:

The ornamental design for a washing machine, as shown and described.

MICHAEL PHILLIP GAULTIER,
MERRILL LAFFAYETTE ALEXANDER,
